(57) **CLAIM**

The ornamental design for a face shield, as shown and described.

DESCRIPTION

FIG. 1 is a front view of embodiment one of a face shield with the back view being a mirror image thereof, showing our new design; and,

FIG. 2 is a front view of embodiment two of a face shield with the back view being a mirror image thereof.

The dot-dash broken lines on the face shield of FIG. 2 are included to show unclaimed fold lines on the article.

1 Claim, 2 Drawing Sheets
